(57) **CLAIM**

We claim the ornamental design for a display tablet enclosure, as shown and described.

DESCRIPTION

Please see co-pending U.S. utility patent application filed on the same day by the same inventors, entitled Security Enclosure For Tablet Display Devices, with application Ser. No. 13/212,770.

FIG. 1 is a front perspective view of a display tablet enclosure embodying the new design.

FIG. 2 is a front perspective view of the display tablet enclosure of FIG. 1 with a front panel open.

FIG. 3 is a top plan view of the display tablet enclosure of FIG. 1.

FIG. 4 is a front elevation view of the display tablet enclosure of FIG. 1.

FIG. 5 is a rear elevation view of the display tablet enclosure of FIG. 1.

FIG. 6 is a left side elevation view of the display tablet enclosure of FIG. 1.

FIG. 7 is a right side elevation view of the display tablet enclosure of FIG. 1.

FIG. 8 is a bottom plan view of the display tablet enclosure of FIG. 1.

FIG. 9 is a front perspective view of a display tablet enclosure embodying the new design, identical to FIG. 1 but with an alternate right side.

FIG. 10 is a front perspective view of the display tablet enclosure of FIG. 9 with a front panel open.

FIG. 11 is a top plan view of the display tablet enclosure of FIG. 9.

FIG. 12 is a front elevation view of the display tablet enclosure of FIG. 9.

FIG. 13 is a rear elevation view of the display tablet enclosure of FIG. 9.

FIG. 14 is a left side elevation view of the display tablet enclosure of FIG. 9.

FIG. 15 is a right side elevation view of the display tablet enclosure of FIG. 9; and,

FIG. 16 is a bottom plan view of the display tablet enclosure of FIG. 9.

The structure illustrated in broken lines is environmental in nature and forms no part of the claimed design.
